UNITED STATES PATENT OFFICE.

GEORGE W. HOCHSPRUNG, OF BROOKLYN, NEW YORK, ASSIGNOR, BY MESNE ASSIGNMENTS, TO JACOB KOTHE, OF JERSEY CITY, NEW JERSEY.

FIRE-ALARM SYSTEM.

1,206,845.

Specification of Letters Patent.

Patented Dec. 5, 1916.

Application filed November 23, 1914, Serial No. 873,437. Renewed April 20, 1916. Serial No. 92,531.

To all whom it may concern:

Be it known that I, GEORGE W. HOCHSPRUNG, a citizen of the United States, residing at Brooklyn, in the county of Kings and State of New York, have invented certain new and useful Improvements in Fire-Alarm Systems; and I do hereby declare the following to be a full, clear, and exact description of the invention, such as will enable others skilled in the art to which it appertains to make and use the same.

The present invention relates to an improved fire alarm apparatus for giving notice of a fire and locating the place whence an alarm is sent in, whether used in municipal systems or in public buildings, apartment houses, hotels and the like.

It has been common hitherto to provide a chain of automatic breakers in series on a normally closed circuit of high resistance, which were combined with relays operating upon a second (and lower resistance) circuit to ring a bell or bells. The arrangement of the succession of makes and breaks provided a code signal differing for each alarm box, whereby the location of the fire was ascertained.

It is the object of the present invention to provide means whereby a single circuit may be used uniting all the alarm boxes and bells in series, for obtaining all the results and advantages offered by the older systems. The advantage of entirely suppressing or doing away with duplicate circuits is obvious, both on account of reduction of expense and because of the decreased repairs and decreased danger of the system getting out of order.

The invention is shown in a preferred embodiment in the accompanying drawing, wherein—

Figure 1 is a diagrammatic representation of the entire system and Fig. 2 is a partial sectional view of a modified form of dash pot.

The main circuit wire is shown at 10, and unites in series the alarm boxes 11 (of any appropriate well known type) and the

alarm bells 12, all of which are supplied by a suitable source of current, as for instance the secondary battery 13, charged by a dynamo 14.

A solenoid 15 has preferably a low resistance coil 16 and a high resistance coil 17, normally in series with each other and the main circuit. Normally this solenoid upholds a core 18, whose lower part only is of magnetic material, and whose extremity is furnished with insulation 19. In its normal position, as shown in Fig. 1, this core holds up the movable member 20 of a by-pass or short-circuiting switch, to the opposite sides of which lead the wires 21 and 22. The former of these wires is connected to one extremity of the united solenoid coils and later is connected between them.

In series with the main circuit is preferably placed any well known type of "two-scale" ammeter 23; and, of course the scale for measurement of small currents is normally in circuit.

I preferably employ a "trouble alarm" bell 24, which may be operated by a suitable local generator 25, when the switch 26 is closed. As shown in Fig. 1, this closure of circuit takes place whenever the switch member 20 moves downward. This trouble alarm is placed at the central station, and serves to give notice of accidental breaks in the main circuit whereby it might be rendered inoperative. It is not an essential of my invention. The ammeter 23 may also be dispensed with.

It is to be understood, that, while I have shown the core of my solenoid actuated by and against gravity, and placed in an upright position, it is within the scope of my invention to employ equivalent forces and different arrangements and shapes of solenoid and core.

When the solenoid is deenergized the movement of the core on release (downward in the drawing) is controlled by a piston 27 on the core, moving within a suitable liquid within the dash pot cylinder 28, provided with a by-pass 29 controlled prefer-

ably by a set screw 30. I prefer to enlarge the upper portion of the cylinder so as to give a quick movement at the end of the up stroke of the core, to break any arc that 5 might form at the switch 20.

If desired, other forms of dash pot may be used. In Fig. 2 I have shown a modification wherein quick downward movement and slow upward movement are secured.

10 Here the by-pass is omitted and the piston 31 has a large valve 32 opening upward only, which valve has an opening 33 permitting passage of liquid on the up stroke.

The operation of my system is as follows—When an alarm box 11 is “pulled”, 15 the main circuit is momentarily opened.

The core 18 drops and the member 20 falls and short circuits the solenoid coil 17, and brings in the second ammeter coil. There is 20 thus prepared a low resistance circuit which is closed when the first circuit closure occurs in the alarm box. This low resistance circuit then affords a current which is competent to ring all the bells, and this ringing 25 lasts until the solenoid 15 has brought the slow moving core back to the normal position shown, when the member 20 is quickly lifted, and the high resistance of the main circuit is restored by bringing the coil 17 30 of the solenoid into circuit again. This operation is repeated for each break of circuit in the alarm box, and the code signal is thus produced.

Various changes may be made in the 35 construction and arrangement of my apparatus without departing from my invention, and I do not limit myself to the details herein shown and described.

What I claim is—

40 1. In an alarm system an automatic make and break alarm box, an electric alarm, a single main circuit uniting said box and alarm, an electro-magnet having its coils normally in series in said main circuit, a 45 switch, an armature in the magnetic field of said coils adapted to control said switch, a shunt around a portion of said coils, said shunt being controlled by said switch to close the same on failure of current in said 50 main circuit, the coils remaining permanently in series being so proportioned as to operate said switch to open it when the remainder of the coils are shunted.

2. In an alarm system, an automatic make 55 and break alarm box, an electric alarm, a single main circuit uniting said box and alarm, an electro-magnetic switch comprising a high and a low resistance coil in series with each other and with said main circuit and having a single armature in the magnetic field of said coils, and a shunt around said high resistance coil, said shunt being controlled by said switch to close the same on failure of current in said main circuit.

3. In an alarm system, an automatic make 65 and break alarm box, an electric alarm, a single main circuit uniting said box and alarm, an electro-magnet having its coils in said circuit, an armature controlled by said magnet adapted to cut resistance out of 70 said circuit without cutting said magnet coils entirely out of circuit when the circuit is opened at said alarm box, and also adapted to restore said resistance when circuit is closed at said alarm box and said electro-magnet thereby energized, and a retarding device for said armature adapted to oppose its rapid movement when attracted by said magnet on closure of circuit at the alarm 75 box.

4. In an alarm system, an automatic make and break alarm box, an electric alarm, a single main circuit uniting said box and alarm, an electro-magnetic switch comprising two sets of coils in series and an armature adapted to shunt one of said sets of coils when the magnet is deenergized, and a retarding means for said armature adapted to oppose its rapid movement when attracted by said magnet, substantially as described. 85

5. In an alarm system, an automatic make and break alarm box, an electric alarm, a single main circuit uniting said box and alarm, a solenoid having its coils connected 95 normally in said main circuit, a switch normally held open by the core of said solenoid, and a shunt around a portion of the coils of said solenoid controlled by said switch, the coils remaining permanently in series being 100 so proportioned as to operate said switch to open it when the remainder of the coils are shunted, substantially as described.

6. In an alarm system, an automatic make and break alarm box, an electric alarm, a 105 single main circuit uniting said box and alarm, a solenoid having a high and a low resistance coil in series with each other and normally included in said main circuit, a switch normally held open by the core of said solenoid, and a shunt around the high resistance coil of said solenoid controlled by said switch, substantially as described. 110

7. In an alarm system, an automatic make and break alarm box, an electric alarm, a 115 single main circuit uniting said box and alarm, a solenoid having its coils connected normally in said main circuit, a dash pot arranged to control the movement of the core of said solenoid, a switch normally held open by the core of said solenoid, and a shunt around a portion of the coils of said solenoid controlled by said switch, substantially as described. 120

8. In an alarm system, an automatic make 125 and break alarm box, an electric alarm, a single main circuit uniting said box and alarm, a solenoid having its coils connected

normally in said main circuit, a switch normally held open by the core of said solenoid, a trouble alarm controlled by said solenoid core, and a shunt around a portion of 5 the coils of said solenoid, controlled by said switch, the coils remaining permanently in series being so proportioned as to operate said switch to open it when the remainder

of the coils are shunted, substantially as described.

In testimony whereof I affix my signature in presence of two witnesses.

GEORGE W. HOCHSPRUNG.
